UNITED STATES PATENT OFFICE

2,046,933

SEWING MACHINE FOR SEAMING AND COVERING THE EDGE PORTIONS OF FABRIC SECTIONS

Joseph Berger, Utica, N. Y., assignor to Union Special Machine Company, Chicago, Ill., a corporation of Illinois

Application January 12, 1933, Serial No. 651,425

30 Claims. (Cl. 112—63)

The invention relates to new and useful improvements in a sewing machine which joins the upturned edge portions of fabric sections and covers the same to form a flat seam.

5 An object of the invention is to provide a machine of the above type wherein the edge portions which have been joined by through and through stitches may be turned down prior to the covering of the same with covering stitches. 10 A further object of the invention is to provide a machine of the above type with trimming devices located in advance of the through and through stitching mechanism for trimming the edges preparatory to the joining of the same and 15 the turning of the edge portions down for covering.

A still further object of the invention is to provide a machine of the above type wherein the through and through stitch forming mechanism and the trimming devices may rise and fall during the stitching operation to accommodate varying thicknesses, and for stitching the fabric sections a uniform distance from the trimmed edges.

25 A still further object of the invention is to provide a machine of the above type wherein there is a presser foot associated with each stitching mechanism, and said presser feet are mounted so that the front foot cooperating with 30 the through and through stitching mechanism may yield independently of the rear foot, and wherein the stitching mechanism for forming the through and through stitches will yield with the associated presser foot.

35 A still further object of the invention is to provide a machine of the above type wherein the presser foot cooperating with the through and through stitch forming mechanism is provided with a channel or groove in its under face 40 for directing the upturned edge portions of the fabric sections, and wherein the wall of the groove opposite the side of the fabric penetrated by the needle serves as a work supporting member.

45 A still further object of the invention is to provide a machine of the above type wherein the presser foot associated with the covering stitching mechanism is provided with a recess or groove at the front end thereof having one 50 wall thereof in line with the work supporting wall of the front presser foot, and a vanishing wall which operates to turn down the edge portions flat against one of the fabric sections for covering.

55 A still further object of the invention is to

provide a machine of the above type wherein the covering stitching forms a twin needle stitch so disposed that the looper thread covers the turned down edge portions, and wherein means is associated with the stitching mechanism for supporting the needle threads for chaining off between stitched articles.

These and other objects will in part be obvious and will in part be hereinafter more fully described.

In the drawings which show by way of illustration one embodiment of the invention—

Figure 1 is a view from the front side of the work supporting arm showing a machine embodying the improvements with certain cover plates removed to show the structure of the machine;

Fig. 18 is a view showing diagrammatically and in transverse section the fabric sections after they have been joined by the through and through stitches and prior to the turning down 45 of the edge portions;

Fig. 19 is a similar view showing the edge portions as covered by the twin needle covering stitches;

Fig. 20 is a view showing diagrammatically in 50 side elevation the needle and looper at the time when the looper point is entering the needle thread loop;

Fig. 21 is a similar view showing the parts in plan view;

55 Fig. 22 is a view showing the looper and needle in side elevation at the time when the needle point is entering the thread triangle;

Fig. 23 is a similar view in plan of the same; and

60 Fig. 24 is a diagrammatic view showing the operation of the thread controlling devices for the thread of the through and through stitching needle.

The invention as shown, is embodied in a 65 sewing machine having a work supporting arm off from the end of which the fabric sections are fed as the edge portions thereof are trimmed, joined and covered. The fabric sections to be joined are fed beneath a presser foot with the edge portions thereof upturned. The presser foot holds the fabric sections on the work supporting arm and guides the same to the trimming devices which trim said upturned edge portions. The trimmed edge portions are then presented to a through and through stitching mech-

anism which includes a needle which is preferably curved and which moves about a center directly above the edge portions. Cooperating with the needle is a thread carrying looper which is given proper movements for forming a 5 two-thread chain stitch. This looper moves about a center above the needle path and crosses the needle path so as to enter the needle loop thrown out by the needle. It is then given its needle avoiding movement. The needle and 10 looper and trimming devices are all so associated with the presser foot as to move up and down therewith under varying thicknesses of fabric passing beneath the presser foot. The presser foot has a groove extending all the way through 15 the bottom surface thereof for directing the upturned edge portions, and the wall of the groove on the opposite side of the fabric sections entered by the needle serves as a support for the material being stitched. There is a rear 20 presser foot which is mounted independent of the front presser foot, and this rear presser foot has a vanishing groove at the forward end thereof, one wall of which is in line with the work supporting wall of the front foot, and is shaped 25 so as to turn down the edge portions after they have been joined by the through and through stitches flat against one of the fabric sections. Associated with the rear presser foot is a stitch forming mechanism which includes two needles 30 mounted beneath a throat plate and movable up through the fabric sections at opposite sides of the turned down edge portions. Cooperating with these two needles is a thread carrying looper which connects the needle thread loops 35 by looper thread loops which form the covering for the turned down edge portions. Associated with the rear presser foot is a loop supporting finger or wire over which the needle thread between successive needle punctures is laid by the 40 feed of the fabric. This finger is withdrawn during each stitch formation and operates as a supporting means for the needle thread loops to insure stitch formation where there is no 45 fabric section being stitched and permits chaining off between fabric sections. It is believed that the invention will be better understood by a more detail description of the illustrated embodiment thereof.

The machine to which the invention is applied is of the type shown in the Christensen and LeVesconte Patent No. 1,741,095, granted December 24, 1929. It will be apparent, however, that the improved stitch forming mechanism may be used in connection with other types of machines. 55 Only a portion of the machine is shown, as the actuating shaft and the feeding mechanism are of the type disclosed in the patent referred to. Said machine includes a supporting standard or bracket 1 having an overhanging portion carrying a horizontal member 2 in which is located a main actuating shaft 3. Said shaft is operated by a belt wheel 4 with which is associated a hand wheel 5. Suspended from this upper horizontal member 2 is a work supporting arm 6 65 which is provided with the usual feeding mechanism including a feed dog 7 which is disposed so as to feed the material being stitched off from the end of the work supporting arm. This feed dog 7 is given the usual four motions so as to 70 engage the fabric and impart thereto a feeding movement.

The material being stitched is supported on this work supporting arm 6. The work supporting arm carries a throat plate 8, which is shown 75

in plan view in Fig. 15. The throat plate is provided with feed slots 9 through which the feed dog operates for the feeding of the fabric. Said throat plate is secured to the work supporting arm by suitable screws, two of which are shown at 10, 10 in Fig. 1 of the drawings. The throat plate extends beyond the end of the work supporting arm 6 and forms the fabric supporting means. Said throat plate has a raised portion centrally thereof as indicated at 11 in Figures 6 and 15. The portions at each side of this centrally raised portion 11 incline downwardly away therefrom. This is for aiding in directing the fabric sections with the edge portions thereof upturned. The fabric portions to be stitched are placed on opposite sides of the work supporting arm and are brought together over the top thereof with their edge portions flat against each other, as clearly shown in Fig. 6 of the drawings, where the fabric sections are indicated at F and F', and the upturned portions are indicated at f and f'. The portion of the feed dog directly beneath this part of the throat plate having these inclined faces meeting at the center of the throat plate, are likewise inclined so as to engage the fabric both at the sides and adjacent the center of the throat plate.

The fabric sections are held on the throat plate by a presser foot 12. The presser foot 12 has a central groove or recess 13 extending all the way through the presser foot from front to rear thereof, and opening at the under side of the foot. The walls of the presser foot at each side of this recess 13 are inclined outwardly and downwardly to conform to the shaping of the throat plate so that the fabric sections with the upturned edge portions guided through the groove or recess 13 will be firmly clamped either against the throat plate or the feed dog as the stitching takes place.

This presser foot 12 is provided with a supporting lug 14 which is clamped to a bracket portion 15 attached to the lower end of a presser bar 16. A leaf spring 17 bears on a lug 18 attached to the upper end of this presser bar. This provides a yielding support for the presser foot so that it may rise and fall with the varying thicknesses of the fabric sections incident to cross seams or the like. The throat plate is rigid and the presser foot is a yielding member which not only rises and falls, as stated, but which can be lifted from the fabric sections when it is desired to remove the same from the machine or to insert new fabric sections for stitching.

The upturned fabric sections are first presented to a trimming mechanism which includes a stationary trimming blade 19 attached to the presser foot by a clamping plate 20, and a clamping bolt 21. The recess or groove 13 in the presser foot extends all the way through the foot as shown in Fig. 13, in the region of the trimming devices and in front thereof. Cooperating with this stationary trimming blade 19 is a movable trimming blade 22. The movable trimming blade 22 is clamped to a head 23 carried by an arm 24 having a ribbed connection to a yoke member 25. The yoke member 25 has a sleeve 26 surrounding the rear presser bar 21 on which said sleeve and yoke member are free to oscillate and move endwise. There is an upper sleeve 28 having a reduced portion 29 extending through a sleeve 30 having a depending arm 31 secured by screws 32, 32 to a collar 33 which is clamped to the presser bar 27. A spring 34 surrounding the presser bar

27 bears on the upper end of the yoke sleeve and yieldingly forces the movable cutting blade downwardly against the stationary shearing blade with which it cooperates. Said movable blade has the usual projecting finger or tongue which overlies the stationary blade and contacts therewith throughout the entire trimming operation. The presser foot is cut away to provide proper clearance for the operation of the movable cutting blade. Mounted on the presser foot 10 is a strip deflector 35 which is shown as moved to inoperative position in Fig. 1. This strip deflector normally extends across the slot in the presser foot and deflects the trimmed off edges away from the stitching mechanism. Inasmuch 15 as the movable cutting blade is yieldingly pressed downward by the spring 34, and the downward movement is limited by the stationary blade carried by the presser foot, the trimming mechanism will rise and fall with the presser foot. 20 The raised portion on the throat plate terminates just at the rear of the trimming blades and the upturned edge portions after they are trimmed pass on through the groove in the presser foot and beneath the lug portion 14 25 which supports the presser foot.

The yoke member 25 carries a ball stud 36. A link 37 engages said ball stud on the yoke and also engages a ball stud 38 attached to an arm 39 carried by a sleeve 40. This sleeve 40 also 30 carries an arm 41 provided with a ball stud 42 to which is attached an eccentric strap 43 cooperating with an eccentric on the main actuating shaft. As the main actuating shaft rotates, it will, through this train of mechanism, 35 impart oscillations to the yoke member and the movable trimming blade carried thereby.

The presser foot is provided with a needle opening 44 therethrough through which a needle 45 passes. The needle penetrates first the fabric 40 section F and then the fabric section F'. The upturned edge portions of the fabric sections contact with the wall 13a of the groove 13 which serves as a fabric supporting wall, resisting the movements of the fabric sections as the needle 45 penetrates the same. The inclined faces on the throat plate are so disposed relative to the slot in the presser foot as to direct the upturned edge portions along this wall 13a. The fabric sections will be guided along said wall, and the 50 needle, which is a curved needle, oscillates, entering the fabric sections from the left, as viewed in Fig. 6. The needle 45 is clamped to an arm 46 by a suitable clamping means, and this arm is in turn clamped to a supporting sleeve 55 mounted for oscillation on a bearing stud 47. Also attached to this sleeve is an arm 48 carrying a ball stud 49 to which a link 50 is attached. The link 50 has a forked connection at its other end with an arm 51 rigidly attached to a shaft 60 52. The shaft 52 carries an arm 53 provided with a ball stud to which a link 54 is connected. The link 54 is connected at its upper end to a ball on the end of a stud 55 which is adjustable in a slot 56 formed in the end of an arm 57. 65 The arm 57 is attached to the outer end of a shaft 58. The shaft 58 is mounted in a needle head and carries inside of the needle head a lever 59. This lever 59 has a forked end 60 carrying a pin to which a link 61 is connected. The 70 link 61 cooperates with a crank 62 formed in the main actuating shaft. As the main shaft rotates, it will oscillate the shaft 58, which in turn oscillates the shaft 52, and this, through the link 50, will oscillate the needle. 75

This bearing stud 47 on which the needle lever oscillates is carried by the bracket 15 which supports the presser foot 12. The needle is, therefore, supported on the presser bar 16 and can move up and down with this presser foot. The needle is an eye-pointed needle of the usual type. After it passes through the fabric sections it throws out a needle loop at the side thereof which is entered by the thread carrying looper 63. Said thread carrying looper 63 is curved so as to lie in a plane parallel with the path or the plane in which the needle oscillates. The looper has a shank portion 64 extending at right angles to the plane of the looper, and this shank portion extends into the sleeve 65 carrying a collar 66 which is clamped to the end of a looper supporting shaft 67. This looper supporting shaft 67 is mounted in an extension 15^a of the bracket 15. This extension is provided with projecting arms carrying spaced bearing sleeves 15^b and 15^c (see Fig. 7). On the opposite end of the looper supporting shaft 67 is an arm 68 carrying a ball stud 69. A link 70 cooperates with this ball stud and also engages a ball stud 71 carried by an arm 72 mounted on a shaft 72^a supported in a bearing sleeve 73 carried by a bracket 74 which is bolted to the main standard or bracket 1 of the machine. The shaft 52 is also journaled in bearing sleeves 74^a and 74^b formed in this bracket 74. Located between these bearing sleeves 74^a and 74^b is an arm 75 which is attached to the shaft 52. There are two arms 75 extending out from the sleeve attached to the shaft 52, and a link 76 is connected to a pin between these two arms 75. This link 76 is also connected to the forked end 77 of an arm attached to the shaft 72^a. This imparts an oscillation to the shaft 72^a, and in turn, through the link, will oscillate the looper shaft, imparting to the looper oscillating movements into and out of the needle thread loop. As shown in full lines in Fig. 4b, the arms 75, 77 are at an acute angle to each other and the looper is at the rear end of its stroke. As shown in Fig. 4a, the arms and the link have moved into alignment, and the looper is about to reach the end of its forward stroke. The arms and the link move slightly past dead center to the broken line position in Fig. 4b, and this is what gives a dwell to the looper at the forward end of its stroke.

The looper supporting shaft is moved endwise by means of an arm 78 freely mounted on the looper shaft and located between the collars 79 and 80 which are fixed to the looper supporting shaft 67. This arm 78 engages a sleeve 81 attached to a yoke 82. The yoke 82 is fixed to a rod 83. Said yoke is made in two parts and includes a sleeve 82^a and also a sleeve 82^b. These two sleeves are mounted on the rod 83 (see Fig. 7), and are connected by a bar 82^c which is integral with sleeve 82^b and bolted to the sleeve 82^a. This rod is mounted for reciprocation in a bearing 84 carried by a bracket 85 which is secured to the needle head by bolts 86 (see Fig. 1). Said bracket 85 has a depending forked arm 87 which straddles the bearing sleeve 15^c in which the looper shaft 67 is mounted for oscillation and endwise movement. The bearing sleeve has flat sides, and is free to rise and fall in the fork of this arm 87. A strut 88 is attached to the forked arm 87 and is also connected to a pin 89 which is attached to the bracket 74.

75. Mounted on the yoke 82 is a ball stud 90. A

link 91 is connected to said ball stud, which in turn is connected to a ball stud 92 carried by an arm at the lower end of a vertical shaft mounted in bearing sleeves 93 and 94 carried by a bracket 95 which is bolted to the frame of 5 the machine. The sleeve 40 is freely mounted on this shaft and oscillates thereon. There is an arm 96 attached to the upper end of the shaft which carries a ball stud 97 cooperating with an eccentric strap 98 which in turn 10 operates with an eccentric on the main actuating shaft 3. As the main actuating shaft rotates, it will, through this link 91, move the yoke 82 back and forth, and the yoke, through connection to the arm 78 will move the looper 15 shaft endwise, thus giving to the looper its 20 needle avoiding movement. The shaft 67 carrying the looper, can, however, move up and down with the presser foot, at which time the arm 78 will slide up or down in the sleeve 81. This 25 provides a means for positively oscillating the looper shaft, and for positively moving it endwise, and at the same time permitting the looper shaft to move up and down with the presser foot. The needle, in its oscillations is moved up 30 and down with the presser foot, and this up and down movement of the looper shaft will maintain the proper cooperative position between the looper and the needle.

As has already been noted, the looper is 35 mounted for oscillation in a vertical plane, the same as the needle. The center of oscillation of the looper is, as noted in Fig. 6, well to the right of the extreme inner position of the point of the needle, and also located close to the extended needle path, and as a consequence, the looper will cross the path of the needle substantially at right angles thereto. The operation of the needle and looper in the forming of a stitch will be possibly better understood from 40 the diagrammatic views shown in Figures 20 to 23. In Figures 20 and 21, the needle has moved to the forward end of its stroke, and is retracted slightly, so as to throw out its needle thread loop. This is accomplished in the usual manner. The needle thread is indicated at n. The looper point is just about to enter this needle thread loop. The looper moves into a needle thread loop and to the end of its stroke, where it comes to a dwell. When the looper is at 45 the forward end of its stroke, it is positioned so that the upper face thereof inclines upwardly away from the point of the looper. As a result, the needle thread loop, due to the tension on the loop, will slide up on the looper, which will raise 50 the loop sufficiently so that the needle on its next stroke can pass beneath the loop. The looper, while at a dwell, is given its needle avoiding movement, and this will carry the needle thread loop over the needle and across the needle to the opposite side thereof, while the looper thread itself, indicated at l, will be laid beneath the needle path and extend across the plane of oscillation of the needle. The needle will, therefore, enter the thread triangle formed by the 55 needle thread loop, the looper thread and the body of the looper. It will be noted that the looper has very little lateral movement, and therefore, the entire stitching elements take up very little room lengthwise of the feed. This 60 enables the stitch forming mechanism to be placed close to the trimmers.

In Fig. 18, the fabric sections indicated at F and F', have the upturned edge portions f and f' trimmed, and a line of stitching s has been 75

formed through these upturned edge portions by the needle 45 and the looper 63 which cooperates therewith. The next step in a flat seam formation is to turn the joined edge portions f and f' into a horizontal position flat against one of the fabric sections. In Fig. 19, these edge portions are shown turned down against the fabric section F' . In order to cover these edge portions, a twin needle stitch forming mechanism is used including two needles and a looper cooperating with both needles. One of the needles forms needle loops s' through the fabric section F , while the other needle forms needle thread loops s^2 through the fabric section F' . The looper thread l' joins these needle thread loops s' and s^2 , and the looper thread loops cover and tie down the edge portions, thus producing a flat seam, as shown in Fig. 19.

The next feature in the machine is the means for turning the edge portion flat against the fabric section F' . This is accomplished by the rear presser foot, which is shown in detail in Figures 8 to 10. The rear presser foot includes a body portion 99 which is attached to the presser bar 27. Said body portion has fabric engaging sections 100, 100 (see Fig. 9). These fabric engaging sections are spaced from each other and located between the same is a yielding foot section 101. This yielding foot section 101 is carried by a supporting post 102 which slides freely in a sleeve bearing formed in the body portion 99. Said post carries a pin 103 which engages a slot in the body portion 99 and this prevents the foot portion from turning. A spring 104 coiled about a stud 105 engages the foot portion 101 and yieldingly presses the same downward. The pin 103 limits the downward movement of the foot portion. A screw 106 threaded into the body portion bears against the end of the screw and serves as a means for varying the spring pressure of the foot against the fabric.

The foot portion 101 extends from a point directly in rear of the front presser foot 12, as shown in Figures 1 and 5, to the rear of the presser foot sections 100. The front portion of this foot 101 is broader and extends all the way across the sections 100, 100, while the rear portion is narrower and lies between said sections 100, 100.

The front ends of the sections 100, 100 are curved upwardly so that the foot will ride easily over a cross seam. This foot is carried by the presser bar 27, and a leaf spring located in the needle head bears on the sleeve 30 which is attached to the presser bar 27, and this yieldingly holds the foot pressed against the fabric.

The presser bar 27 has a reduced section at its lower end extending through the sleeve 26 attached to the yoke operating the trimmer. The bracket 15 has a sleeve 107 attached thereto which extends up into the sleeve 26 so that the trimmer yoke oscillates on this sleeve 107. There is a shoulder in the presser bar 27 which limits the downward movement of the presser bar 27 relative to the bracket 15. The rear presser foot is secured to the presser bar 27 by a screw 108. The foot is attached to the bar at a slight distance beneath the bracket 15. There is a washer 109 surrounding the bar and lying on the presser foot shank. This allows a limited movement of the rear foot up and down through the action of varying thicknesses of fabric beneath the same, which movement is independent of any up and down movements imparted to

the front presser foot, trimmer and front stitching mechanism. The presser bar 27 is raised by a hand lever 110 (see Fig. 2) which is connected through a train of mechanism with the bar within the needle head. When the presser foot is lifted, the washer 109 contacting with the bracket 15 will lift the bracket 15, and the front presser foot, so that by the single lever, both of the presser feet may be raised from engagement with the fabric for permitting the changing of the fabric. At the same time, the rear presser foot has this independent yielding movement.

The rear presser foot is provided with needle slots 111, 111, between which is a tongue 112 over which the looper thread loop is laid. The looper thread loops joining the needle thread loops will pass off from the rear end of the stitch tongue. In the under face of the fabric engaging portion 101 is a groove or recess 113. This groove, as shown in Figures 9 and 14, has a substantially vertical wall 114 which is in alignment with the wall in the front foot opposite the fabric supporting wall 13a. The wall of the rear foot at the opposite side and upper side of the groove 113 is curved as indicated at 115 and vanishes into the bottom of the foot with the wall 114, and this wall is so shaped as receive the upturned edge portions passing off from the vertical fabric supporting wall 13a and turns the same down into horizontal position just as they reach the needle slots 111, 111, or the region of stitch formation of the cover seaming mechanism. The slot, as shown, terminates slightly in rear of these needle openings 111, but insures that the edge portions are turned down flat before the region is reached where the stitches are drawn taut.

The throat plate 8 is provided with needle slots 116, 116, and with a feed slot 117 which extends between the needle slots. This operates on the fabric sections directly beneath the turned down portions, and insures a proper feeding of the same beneath the rear presser foot. The presser foot is substantially flat or horizontal in the region of the rear presser foot. The raised portion 11 terminates substantially at the rear end of the front presser foot so as to allow the seam to be flat with the edge portions turned flat against one of the fabric sections when the covering stitching mechanism functions.

The covering stitching mechanism includes two needles 118 and 119. These needles are both clamped to a needle head 120. The needle head 120 has a groove in the side face thereof for the needle 118, and the needle is held in the groove by a clamping member 121. There is a similar groove and clamping member on the opposite side of the needle head 120 for the needle 119. This needle head is carried by a lever member 122 which is mounted for oscillation on a stud 123. This stud is fixed to a rod 124 functioning as a needle bar. The lever 122 is pivoted at 125 to a stud carried by the throat plate 8. As the rod or needle bar 124 reciprocates, it will cause the lever 122 to oscillate about the stud 125 and this will in turn cause the needles to move up through the fabric sections. The needles pass up through the needle openings 116, 116 in the throat plate, then through the fabric sections, and then through the needle slots 111 in the rear presser foot. The needles are curved and are eye-pointed, and each is provided with a thread. It will be noted that the needles pass

through the fabric sections in substantially a vertical direction, but each needle moves in a path curving toward the horizontal within the work arm so that the needles can be mounted in a relatively small work arm and have the necessary stroke given thereto for the penetrating of the fabric and the stitch formation. The rod or needle bar 124 is rigidly connected to a link 126 which in turn is pivoted at 127 to a rod 128 reciprocating in a slot 129. The rod 128 is connected by a link 130 to a rock lever 131. Said rock lever is pivoted at 132 to the frame, and carries a ball stud 133 which in turn is connected to a link 134 engaging at its upper end a ball stud 135 carried by a crank on the main actuating shaft 3. The rod 128 reciprocates in a right line in a sleeve 129 and imparts an endwise movement to the link 126 which in turn reciprocates the rod or needle bar 124 and causes the needles to oscillate in the manner described above. The link 126 is provided with right and left-hand threads so that it may be lengthened or shortened for varying the oscillating position of the needles.

Cooperating with the needles above the presser foot is a looper 136. The looper is a thread carrying looper and will first pass into the needle thread loop formed by the needle 118 and then into the needle thread loop formed by the needle 119. This looper is oscillated back and forth in a vertical plane, substantially at right angles to the line of feed. The looper is also given a needle avoiding movement so that after the looper has entered the needle thread loops, it moves laterally and positions the thread triangles for the respective needles to enter. This stitch forming mechanism is the well-known twin needle stitch forming mechanism, and further description of the stitch formation is not thought necessary.

The looper 136 oscillates in a vertical plane and is provided with a shank 137 which extends at right angles to said plane of oscillation. The shank 137 is clamped in the end of an arm 138 carried by a sleeve 139. This sleeve 139 is mounted for oscillation and endwise movement on a supporting rod 140 carried by a depending member 141 formed integral with the bracket 85. Said sleeve 139 has attached thereto a projecting arm 142 carrying a ball stud to which a link 143 is connected. The link 143 at its other end is attached to a ball stud 144 mounted for adjustment in a slot 145 carried by an arm 146 which is fixed to the shaft 58. As the shaft 58 oscillates, it will, through the link 143, impart oscillations to the sleeve 139 and to the looper 136. This link 143 is connected to a ball stud at each end and this permits the sleeve 139 to move endwise of the rod 140 as well as to oscillate on said rod. Fixed to the end of the rod 83 is an arm 147. This arm is provided with a collar 148 (see Fig. 1) which engages the extension 139a of the sleeve 139 (see Fig. 2). On the end of this extension is clamped a collar 149. The arm 146 moves laterally with the endwise movements of the rod 83 and this will shift the sleeve 139 endwise on the rod 140, at the same time permitting the sleeve to oscillate. The rod 83, as has been described above, is utilized for giving lateral movements to the looper which cooperates with the front needle. It likewise gives the lateral movements to this looper cooperating with the rear needles. The rear looper has no up and down movement relative to the rear presser foot,

but moves in a fixed path relative to the needle head.

In order to provide a means for forming stitches when there is no fabric in the machine, a stitch finger or wire 150 has been provided (see 5 Figures 8 and 9). This finger is mounted for reciprocation in a passageway formed in the fabric engaging member 101 of the rear presser foot. It passes across the slots alongside of the stitch tongue 112 and through the stitch finger. 10 The stitch finger 150 moves in a path at right angles to the line of feed. It is in this forward position as shown in Fig. 9 when the needles penetrate the fabric, and after the looper has entered the needle thread loops, so as to hold the same, 15 then the stitch finger or wire 150 is quickly retracted. At this time the needles are withdrawn from the fabric and the feed takes place. As the looper retracts and the needles move up to penetrate the fabric, the stitch finger is quickly 20 projected forward and remains across the slots during the rising of the needles. If there is no fabric in the machine, then the needle thread between consecutive stitches, as the needles rise, will be laid over this finger or wire 150. It takes 25 the place of the fabric and supports the needle thread loops. Otherwise, there would be no means for anchoring the needle thread loops and no loop would be formed which the looper could enter. It is retracted, as noted above, 30 so as to permit the feed after the loop formation has been effected. The purpose of this finger or wire 150 is solely to insure stitch formations when there is no fabric in the machine, and this permits the chaining between fabric sections. 35 This chaining means in connection with a twin needle stitch forming mechanism may be used in other types of machines, and with any twin needle stitching mechanism, and is not limited in its use to the particular type of machine shown, 40 or in combination with the particular features described.

The stitch finger or wire 150 is fixed to a cross-head 151 mounted for reciprocation on two rods 152 and 153 which are rigidly carried by the 45 yielding fabric engaging portion 101 of the rear presser foot. These rods, of course, move up and down with the yielding section of the presser foot, and also with the presser foot as a whole. The crosshead 151 has an upstanding rib 154 50 which engages between spaced ribs on a member 155. This member 155 is clamped to the end of a rod 156 by clamping screws 157. Extending laterally from the body portion of the presser foot is an arm 158 which is in the form of a 55 sleeve, and in this sleeve the rod 156 is mounted for endwise reciprocation. There is a slot 159 in one side of the arm which leads to the inner recess thereof, and a stud 160 is threaded into the rod 156 and projects out through the slot 60 158. A link 161 is connected to the stud and at its outer end is pivoted to an arm 162 attached to a short shaft 163. This shaft carries an arm 164 which is pivoted at its upper end to a link 165, and the link 165 in turn is pivoted to 65 a stud 166 carried by a sleeve 167 which slides freely on the presser bar 16. The sleeve 167 is provided with a lug 168 to which a short link 169 is connected. The upper end of this link 169 is in turn attached to an arm 170 fixed to the shaft 70 58. As the shaft 58 oscillates, it will move the sleeve 167 up and down on the presser bar, and this will oscillate the arm 162 and impart endwise movement to the crosshead carrying the stitch finger or wire 150. It will be noted from 75

Fig. 17, that the link 165 is in an angular position relative to the path of movement of the sleeve when said sleeve is at the upper end of its stroke, and it moves to a horizontal position, 5 or slightly below the same when the sleeve is at the lower end of its stroke. As a result, the finger 150 is moved very quickly forward to the end of its stroke where it is given a dwell, and it is quickly retracted to permit the thread loops 10 laid over the same during chaining to be released and the feed of the same to take place.

The thread controlling mechanism has been provided for the needle 45. This thread controlling mechanism includes a thread guide 171 15 which is attached to the frame of the machine so that it may be adjusted vertically. Mounted on the shaft 163 for movement with the arm 164 is a wire 172 having a thread guiding hook 173. The needle thread indicated at *n* passes through 20 the thread guide 171 and the thread guiding hook 173. It also passes through an eye 174 on a bracket 175 attached to the arm 170. As shown diagrammatically in Fig. 24, the bracket 175 is shown in full lines at its extreme lowest position 25 and in broken lines at its extreme upper position. It will be noted that the wire 172 moves toward and from the thread guide 171. It moves toward the thread guide when the bracket 175 is moving to its extreme upper position, so 30 that while said thread eye formed in the bracket 175 is taking up on the thread, the thread guiding hook 173 is giving up a certain amount of thread, and this will reduce, to a certain extent, the amount of thread that is taken up. 35 The purpose is to utilize this arm 170 which has a relatively long stroke for taking up an amount of thread which is slightly less than would normally be taken up by the movement of the thread eye 174. These parts are so timed 40 that when this thread eye 174 reaches the upper end of its stroke, the needle is retracted from the fabric, the feed is taking place, and the stitch is being set.

It is thought that the operation of the machine will be obvious from the description which 45 has been given in detail of the mechanisms which cooperate to produce the flat seam described. The edge portions are upturned and trimmed and then passed to the stitching mechanism which joins the edge portions. This stitching mechanism, which includes a needle and looper, is so mounted that it can move up and down with the presser foot with which it is associated. Likewise, the trimming devices 50 which trim the edges move up and down with the presser foot so that this line of stitching which joins the fabric sections will always be placed in the fabric sections a given distance from the trimmed edges, regardless of cross 55 seams or varying thicknesses in the fabric, which may raise or lower the position of the presser foot. After the edges are joined, they pass beneath the second presser foot which has a receiving groove or recess shaped so as to 60 turn down the joined edges flat against one of the fabric sections. While passing beneath this foot, two needles pass up through the fabric sections beneath the work support, and the thread carrying looper above the fabric sections 65 cooperates with the needles for interlocking the needle thread loops in the looper thread loop which covers the turned down edge portions. In order that this stitching mechanism may function to chain off between articles, a thread 70 finger is provided which moves through the 75

presser foot and the stitch finger and is timed so that the needle threads are laid across this finger by the feed and support the thread so that loops may be formed for the looper to enter. After the thread loops are enchain, then the 5 stitch finger is retracted so as to permit said enchain thread loops to be fed.

It is obvious that many changes may be made in the stitch forming devices and the parts associated therewith, and also in the specific 10 structures used in connection with each of the various mechanisms described without departing from the spirit of the invention as set forth in the appended claims.

Having thus described the invention, what I 15 claim as new and desire to secure by Letters-Patent, is—

1. A sewing machine comprising a work support, a feeding mechanism, a stitch forming mechanism for joining the edge portions of 20 fabric sections, means for turning down both of the joined edge portions flat against one of the fabric sections and a second stitch forming mechanism for covering and securing the turned down edge portions to the fabric sections by 25 covering stitches passed through the respective fabric sections at each side of the turned down edge portions and adjacent the same.

2. A sewing machine comprising a work support, a feeding mechanism, a stitch forming 30 mechanism for joining the edge portions of fabric sections, means for turning down both of the joined edge portions flat against one of the fabric sections, and a two-needle stitch forming mechanism for passing needle thread 35 loops through the respective fabric sections at each side of the turned down edge portions and adjacent the same and for joining said needle thread loops with a thread for covering said turned down edge portions. 40

3. A sewing machine comprising a work support, a feeding mechanism, a stitch forming mechanism for joining the edge portions of fabric sections, means for turning down both of the joined edge portions flat against one of the 45 fabric sections, and a two-needle stitch forming mechanism for passing needle thread loops upwardly through the respective fabric sections at each side of the turned down portions and adjacent the same and for locking said needle 50 thread loops with the looper thread which covers and secures the turned down edge portions to the fabric sections.

4. A sewing machine comprising a work support, a feeding mechanism, stitch forming 55 mechanism for joining the edge portions of fabric sections, means for trimming the edge portions of fabric sections and directing the same to said stitch forming mechanism, means for turning down both of the joined edge portions flat against one of the fabric sections, and a second stitch forming mechanism for covering and securing the turned down edge portions to the fabric sections by covering stitches passed through the respective fabric sections at each 60 side of the turned down edge portions and adjacent the same.

5. A sewing machine comprising a work support, a feeding mechanism, stitch forming mechanism for joining the edge portions of 70 fabric sections, means for trimming the edge portions of fabric sections and directing the same to said stitch forming mechanism, means for turning down both of the joined edge portions flat against one of the fabric sections, and 75

a two-needle stitch forming mechanism for passing needle thread loops through the respective fabric sections at each side of the turned down edge portions and adjacent the same and joining the same with a covering thread for covering and securing the turned down edge portions to the fabric sections.

6. A sewing machine comprising a work support, a feeding mechanism, stitch forming mechanism for joining the edge portions of fabric sections, means for trimming the edge portions of fabric sections and directing the same to said stitch forming mechanism, means for turning down both of the joined edge portions flat against one of the fabric sections, and a two-needle stitch forming mechanism for passing needle thread loops upwardly through the respective fabric sections at each side of the turned down edge portions and adjacent the same and for locking said needle thread loops by looper thread loops which cover and secure the edge portions to the fabric sections.

7. A sewing machine comprising a work support, a feeding mechanism, a presser foot cooperating with said feeding mechanism for directing the upturned edge portions of fabric sections, a stitch forming mechanism for joining the upturned edge portions including a needle and a looper, a second presser foot cooperating with said feeding mechanism and having means for turning down both of the joined edge portions flat against one of the fabric sections, and a second stitch forming mechanism for covering and securing the turned down edge portions by covering stitches passed through the respective fabric sections at each side of the turned down edge portions and adjacent the same.

8. A sewing machine comprising a work support, a feeding mechanism, a presser foot cooperating with said feeding mechanism for directing the upturned edge portions of fabric sections, a stitch forming mechanism for joining the upturned edge portions including a needle and a looper, a second presser foot cooperating with said feeding mechanism and having means for turning down both of the joined edge portions flat against one of the fabric sections, and a two-needle stitch forming mechanism including needles mounted beneath the work support for carrying needle thread loops up through the respective fabric sections at each side of the turned down edge portions and adjacent the same, and a looper mounted above the work support and cooperating with said needles for covering and securing the turned down edge portions to the fabric sections.

9. A sewing machine comprising a work support, a feeding mechanism, a presser foot cooperating with said feeding mechanism for directing the upturned edge portions of fabric sections, a stitch forming mechanism for joining the upturned edge portions including a needle and a looper, a second presser foot cooperating with said feeding mechanism and having means for turning down both of the joined edge portions flat against one of the fabric sections, and a two-needle stitch forming mechanism including needles mounted beneath the work support and operating to pass needle thread loops up through the fabric sections at each side of the turned down edge portions, a thread carrying looper mounted above the work support and cooperating with both needles for covering and securing the turned down edge portions to the fabric sections, and means cooperating with said two-

needle stitch forming mechanism for supporting the needle threads so that enchain thread loops may be formed thereby when there is no fabric to be stitched.

10. A sewing machine comprising a work support, a feeding mechanism, a presser foot cooperating with said feeding mechanism and having a slot for directing the upturned edge portions of fabric sections, a throat plate having inclined meeting surfaces disposed relative to the slot in the presser foot so as to direct the edge portions of the fabric sections through said slot with said edge portions contacting with one of the walls of said slot, a stitch forming mechanism including a needle, operating to penetrate the fabric sections while in engagement with the wall of the slot, a looper cooperating with said needle, means for turning down both of the joined edge portions flat against one of the fabric sections, and a second stitch forming mechanism disposed relative to the turned down edge portions so as to form covering stitches passing through the respective fabric sections adjacent the turned down edge portions and overlying the same.

11. A sewing machine comprising a work support, a feeding mechanism, a presser foot cooperating with said feeding mechanism and having a slot for directing the upturned edge portions of fabric sections, a throat plate having inclined meeting surfaces disposed relative to the slot in the presser foot so as to direct the edge portions of the fabric sections through said slot with said edge portions contacting with one of the walls of said slot, a stitch forming mechanism including a needle, operating to penetrate the fabric sections while in engagement with the wall of the slot, a looper cooperating with said needle, a trimming mechanism operating in advance of the needle for trimming the upturned edge portions, means for turning down both of the joined edge portions flat against one of the fabric sections, and a second stitch forming mechanism disposed relative to the turned down edge portions so as to form covering stitches passing through the respective fabric sections adjacent the turned down edge portions and overlying the same.

12. A sewing machine comprising a work support, a feeding mechanism, a presser foot cooperating with said feeding mechanism and having a slot for directing the upturned edge portions of fabric sections, a throat plate having inclined meeting surfaces disposed relative to the slot in the presser foot so as to direct the edge portions of the fabric sections through said slot with said edge portions contacting with one of the walls of said slot, a stitch forming mechanism including a needle operating to penetrate the fabric sections while in engagement with the wall of the slot, a looper cooperating with said needle, and means for supporting said presser foot, needle and looper whereby said presser foot, needle and looper may rise and fall with varying thicknesses of material and the stitch forming devices operate in a predetermined position relative to the presser foot for all positions thereof.

13. A sewing machine comprising a work support, a feeding mechanism, a presser foot cooperating with said feeding mechanism and having a slot for directing the upturned edge portions of fabric sections, a throat plate having inclined meeting surfaces disposed relative to the slot in the presser foot so as to direct the edge portions

of the fabric sections through said slot with said edge portions contacting with one of the walls of said slot, a stitch forming mechanism including a needle, operating to penetrate the fabric sections while in engagement with the wall of the slot, a looper cooperating with said needle, a trimming mechanism operating in advance of the needle for trimming the upturned edge portions, and means for supporting the trimming mechanism, the stitch forming mechanism and the presser foot whereby the presser foot, trimming mechanism and stitch forming mechanism may rise and fall with varying thicknesses of the fabric and the stitch forming mechanism and trimming mechanism will operate in a predetermined position relative to the presser foot for all positions thereof.

14. A sewing machine comprising a work supporting arm, a feeding mechanism including a feed dog for feeding the material off from the end of the work supporting arm, a presser foot cooperating with said feeding mechanism and work support for directing the upturned edge portions of fabric sections, a stitch forming mechanism including a needle movable through the fabric sections in substantially a horizontal line, a thread carrying looper cooperating with said needle, said presser foot being mounted so as to move up and down with varying thicknesses of fabric, and said needle and looper being mounted so as to move with the presser foot and operate on said fabric sections in a predetermined position relative thereto for all positions of the presser foot, means for turning down both of the joined edge portions flat against one of the fabric sections, and a second stitch forming mechanism disposed relative to the turned down edge portions so as to form covering stitches passing through the respective fabric sections adjacent the turned down edge portions and overlying the same.

15. A sewing machine comprising a work supporting arm, a feeding mechanism for feeding fabric sections off from the end of said arm, a presser foot having a slot for directing upturned edge portions of fabric sections, a stitch forming mechanism including a curved needle mounted for oscillation about an axis located directly above the edge portions of the fabric sections, a thread carrying looper cooperating with said needle and mounted for oscillation about an axis parallel with the axis of the needle above the needle path and so that the looper crosses the path of the needle substantially at right angles when entering the needle thread loop, means for oscillating said looper, and means for giving to said looper a lateral needle avoiding movement.

16. A sewing machine comprising a work supporting arm, a feeding mechanism for feeding fabric sections off from the end of said arm, a presser foot having a slot for directing upturned edge portions of fabric sections, a stitch forming mechanism including a curved needle mounted for oscillation about an axis located directly above the edge portions of the fabric sections, a curved thread carrying looper mounted for oscillation about an axis parallel with the axis of the needle and located above and adjacent the needle path whereby said looper when entering the needle thread loop crosses the path of the needle substantially at right angles, and whereby the curvature of the looper will cause the needle thread loop to slide upwardly thereon during the formation of the thread triangle so that the needle may pass beneath the needle

thread loop as it enters said triangle, means for oscillating said looper, and means for giving to said looper a lateral needle avoiding movement.

17. A sewing machine comprising a work supporting arm, a feeding mechanism for feeding fabric sections off from the end of said arm, a presser foot having a slot for directing upturned edge portions of fabric sections, a stitch forming mechanism including a curved needle mounted for oscillation about an axis located directly above the edge portions of the fabric sections, a curved thread carrying looper mounted for oscillation about an axis parallel with the axis of the needle and located above and adjacent the needle path whereby said looper when entering the needle thread loop moves from a point above to a point below the path of the needle and substantially at right angles and whereby the curvature of the looper will cause the needle thread loop to slide upwardly thereon during the formation of the thread triangle so that the needle may pass beneath the needle thread loop as it enters said triangle, and means for oscillating said looper and giving thereto a dwell at the forward end of its stroke.

18. A sewing machine comprising a work supporting arm, a feeding mechanism for feeding fabric sections off from the end of said arm, a presser foot having a slot for directing upturned edge portions of fabric sections, a stitch forming mechanism including a curved needle mounted for oscillation about an axis located directly above the edge portions of the fabric sections, a thread carrying looper cooperating with said needle and mounted for oscillation about an axis above the needle path and so that the looper crosses the path of the needle substantially at right angles when entering the needle thread loop, means for oscillating said looper, means for giving to said looper a needle avoiding movement, means for supporting said presser foot whereby it may move up and down with the fabric, said needle and said looper being carried by the supporting means for the presser foot so as to move up and down therewith, means for turning down both of the joined edge portions flat against one of the fabric sections, and a second stitch forming mechanism disposed relative to the turned down edge portions so as to form covering stitches passing through the respective fabric sections adjacent the turned down edge portions and overlying the same.

19. A sewing machine including in combination a work support, a feeding mechanism, a presser foot for directing the upturned edge portions of fabric sections, stitch forming mechanism associated therewith for joining said edge portions including a needle movable in substantially a horizontal direction through the fabric sections, a thread carrying looper cooperating therewith, means for oscillating the needle, means for oscillating the looper, a second stitch forming mechanism in rear of the first-named stitch forming mechanism and operating to cover the joined edges of the fabric sections, said second stitch forming mechanism including two needles mounted beneath the work support and movable upwardly through the fabric sections, a thread carrying looper cooperating with said needles, means for oscillating said thread carrying looper, and common means for giving to the looper associated with the first stitch forming mechanism and the looper associated with the second stitch forming mechanism a lateral needle avoiding movement.

20. A sewing machine including in combination

- a work support, a feeding mechanism, a presser foot for directing the upturned edge portions of fabric sections, stitch forming mechanism associated therewith for joining said edge portions 5 including a needle movable in substantially a horizontal direction through the fabric sections, a thread carrying looper cooperating therewith, means for oscillating the needle, means for oscillating the looper, a second stitch forming mechanism in rear of the first-named stitch forming mechanism and operating to cover the joined edges of the fabric sections, said second stitch forming mechanism including two needles mounted beneath the work support and movable 10 upwardly through the fabric sections, a thread carrying looper cooperating with said needles, means for oscillating said thread carrying looper, common means for giving to the looper associated with the first stitch forming mechanism and the looper associated with the second stitch forming mechanism a lateral needle avoiding movement, and means for supporting said presser foot and the first-named stitch forming mechanism for vertical movement as 15 the thickness of the fabric varies.
21. A sewing machine comprising a work support, a feeding mechanism, a presser foot for directing the upturned edge portions of fabric sections, a needle and a looper mounted above the work support for joining the upturned edge portions, a second presser foot in rear of the first-named presser foot, a stitching mechanism associated with said last-named presser foot, including needles mounted beneath the work support and passing needle thread loops upwardly through the fabric sections at each side of the joined edge portions, a thread carrying looper cooperating with said needles, and means for supporting said presser foot and the first-named 20 needle and looper whereby the presser foot may move up and down with the fabric sections and said needle maintained in a predetermined position relative to the presser foot.
22. A sewing machine comprising a work support, a feeding mechanism, a presser foot for directing the upturned edge portions of fabric sections, a needle and a looper mounted above the work support for joining the upturned edge portions, a second presser foot in rear of the first-named presser foot, a stitching mechanism associated with said last-named presser foot, including needles mounted beneath the work support and passing needle thread loops upwardly through the fabric sections at each side of the joined edge portions, a thread carrying looper cooperating with said needles, means for supporting said presser foot and the first-named needle and looper whereby the presser foot may move up and down with the fabric sections and said needle maintained in a predetermined position relative to the presser foot, and a trimming mechanism for trimming the fabric sections associated with said first-named presser foot and movable up and down therewith.
23. A sewing machine comprising a work support, a feeding mechanism, a presser foot for directing the upturned edge portions of fabric sections, a needle and a looper mounted above the work support for joining the upturned edge portions, a second presser foot in rear of the first-named presser foot, a stitching mechanism associated with said last-named presser foot, including needles mounted beneath the work support and passing needle thread loops upwardly through the fabric sections at each side of the joined edge portions, a thread carrying looper cooperating with said needles, means for supporting said presser foot and the first-named needle and looper whereby the presser foot may move up and down with the fabric sections and said needle maintained in a predetermined position relative to the presser foot, and a stitching mechanism including needles located beneath the work support for passing thread loops upwardly through the fabric being stitched, a thread carrying looper cooperating with said needles above the work support, and a finger extending at right angles to the line of feed and supporting the needle threads for forming enchain thread loops when there is no fabric being stitched.
24. A sewing machine comprising a work support, a feeding mechanism, a two-needle stitch forming mechanism including needles located beneath the work support for passing thread loops upwardly through the fabric being stitched, a thread carrying looper cooperating with said needles above the work support, and a finger extending at right angles to the line of feed and supporting the needle threads for forming enchain thread loops when there is no fabric being stitched.
25. A sewing machine comprising a work support, a feeding mechanism, a two-needle stitch forming mechanism including needles located beneath the work support for passing thread loops upwardly through the fabric being stitched, a thread carrying looper cooperating with said needles above the work support, a finger supporting the needle threads for forming enchain thread loops when there is no fabric being stitched, and means for reciprocating said thread supporting finger in a direction at right angles to the feed, said means being timed so as to position said finger so that the threads between stitches are laid over the finger by the feed and for retracting said finger after the stitches have been formed to permit the feeding of the enchain thread loops.
26. A sewing machine comprising a work support, a feeding mechanism, a presser foot co-operating with said feeding mechanism and having needle openings therethrough and a stitch tongue between said openings, needles mounted beneath the work support and movable up through the presser foot, a looper mounted above the presser foot and cooperating with said needles, said presser foot and stitch tongue having a passageway therethrough in rear of the needle openings, a stitch finger operating in said passageway, and means for reciprocating the same timed relative to the movements of the needle and the feed so that the needle thread is laid over said finger between stitches and the finger is retracted to permit the feeding of the enchain thread loops.
27. A sewing machine comprising a work support, a feeding mechanism, a presser foot having needle openings and a stitch tongue therebetween, stitching mechanism including a pair of needles operating respectively in said openings, a thread carrying looper cooperating with said needles, said presser foot and stitch tongue having a passageway therethrough at right angles to the line of feed, a stitch finger operating in said passageway and means for reciprocating the same timed relative to the movements of the needle and the feed so that the needle thread is laid over said finger between stitches and the finger is retracted to permit the feeding of the enchain thread loops.

said finger timed with said needles and feed so that the needle threads are laid over the finger by the feed and supported thereby while the looper is entering the needle thread loops, and 5 whereby said finger is retracted to permit the feeding of the enchain thread loops.

28. A sewing machine comprising a work support, a feeding mechanism, a presser foot co-operating with said feed and having a recess 10 adapted to receive and direct the upturned edges of fabric sections, a stitch forming mechanism associated with said presser foot for joining the upturned edge portions, a presser foot in rear of the first-named presser foot and having a 15 recess in the front end thereof shaped so as to turn down both of the joined edge portions flat against one of the fabric sections, said last-named presser foot having needle openings at opposite sides of the turned down edge portions, 20 a stitch tongue disposed between said openings, needles mounted beneath the work support for passing needle thread loops upwardly through the fabric sections at each side of the stitch finger and the turned down edge portions, and a 25 looper located above said last-named presser foot and cooperating with said needles for laying looper thread loops over said stitch tongue for covering the turned down edge portions.

29. A sewing machine comprising a work supporting arm, feeding means for feeding the

fabric sections off from the end of said arm, a stitch forming mechanism including curved needles, a lever member mounted within said work supporting arm at the free end thereof and carrying said needles, said lever member being pivoted to the work supporting arm so that said needles will pass in substantially a vertical line through the fabric sections, a looper co-operating with said needles above the work supporting arm, and means extending lengthwise 10 of said arm for oscillating said lever member. 5

30. A sewing machine comprising a work supporting arm, feeding means for feeding the fabric sections off from the end of said arm, a stitch forming mechanism including curved 15 needles, a lever member mounted within said work supporting arm and carrying said needles, said lever member being pivoted to the work supporting arm at the free end thereof so that said 20 needles will pass in substantially a vertical line through the fabric sections, a looper cooperating with said needles above the work supporting arm, means extending lengthwise of said arm for oscillating said lever member, said last- 25 named means including a supporting sleeve, a bar movable endwise of said supporting sleeve, and a link connecting said bar to said lever member.
